UNITED STATES PATENT OFFICE.

SIMON LAKE, OF MILFORD, CONNECTICUT.

SUBMARINE WORKING AND EXPLORATION VESSEL.

1,356,773.

Specification of Letters Patent. Patented Oct. 26, 1920.

Application filed December 30, 1916. Serial No. 139,819.

To all whom it may concern:

Be it known that I, SIMON LAKE, a citizen of the United States, residing at Milford, in the county of New Haven and State of Connecticut, have invented certain new and useful Improvements in Submarine Working and Exploration Vessels, of which the following is a specification.

This invention relates to improvements in submarine working and exploration vessels, and particularly to improvements in the constructions shown in Letters Patents Nos. 738,206, 760,457; 867,984; and 1,097,722, granted to me Sept. 8, 1903; May 24, 1904; Oct. 15, 1907; and May 26, 1914, respectively.

The object of my present invention is to simplify and improve upon the construction of such apparatus as shown in my aforesaid 20 patents, and to provide an apparatus for taking observations of, and for surveying water-beds whereby the accurate topography of water-beds may be obtained, and whereby dredging and other operations may be carried out at considerable depths below the 25 surface of the water without the use of divers and without subjecting the operators to the discomforts experienced by divers when compelled to work at such depths.

The invention comprises a submersible vessel journaled at one end of a tube, and communicating therewith, said tube having its upper end journaled within a wall or recess formed forward in a surface vessel and having lines connected thereto for holding the submersible vessel in a level position and against excessive lateral movement under all conditions of submergence. The invention further comprises a submersible vessel having excavating devices designed for cutting into and loosening the material of a water-bed, combined with apparatus for collecting the loosened material and delivering it to a surface vessel or to barges 40 operating in connection with the apparatus. The invention also comprises means for steering the submersible vessel over the course being operated upon. The invention, finally, comprises certain novel features of construction and arrangement as will be hereinafter fully described and claimed.

In the drawings, illustrating the invention, in the several figures of which like parts are similarly designated, Figure 1 is a diagrammatic side elevation illustrating my invention in use. Fig. 2 is a sectional

side elevation of the submersible vessel and the lower end of the tube connected thereto, and Fig. 3 is a plan view of the same, the tube being shown locked to the vessel, as 60 when the latter is being towed upon the surface of the water. Fig. 4 is a horizontal section drawn on the line *a*—*a* of Fig. 2, the tube being shown in the position illustrated in dotted lines in Fig. 2. Fig. 5 is 65 a vertical longitudinal section drawn on a larger scale on the line *b*—*b* of Fig. 4. Fig. 6 is a transverse section drawn on a larger scale on the line *c*—*c* of Fig. 4. Fig. 7 is a transverse section drawn on a larger scale 70 on the line *d*—*d* of Fig. 4. Fig. 8 is a vertical section drawn on a larger scale on the line *e*—*e* of Fig. 4. Fig. 9 is a horizontal sectional plan view drawn on a larger scale 75 on the line *f*—*f* of Fig. 1, illustrating the arrangement for journaling the upper end 80 of the tube in the well of the surface vessel. Fig. 10 is a side elevation of the same.

1 designates a surface vessel of any approved design having a well or recess 2 80 opening through its forward end. In the after end of the well or recess is yieldingly supported the upper end of a tube 3, to the lower end of which is journaled my improved submersible vessel 4. The vessel 4 85 is here shown rectangular in cross-section, having tapering bow and stern portions. The vessel 4 is provided at its after end with a recess 5, in the vertical side walls 6 (Fig. 4) of which is journaled the lower end 90 of the tube 3. Stuffing boxes 7 are provided to prevent ingress of water to the interior of the vessel 4 around the journals of the tube 3. The vessel is divided transversely by partitions 8 and 9, (Fig. 4), and horizontally by a partition 10, (Figs. 2, 7, and 8), the transverse partitions 8 and 9, and the horizontal partition 10 providing a water-ballast compartment or compartments 11 in the bottom of, and in the after end 95 of the vessel; and the space above the partition 10, between the transverse partitions 8 and 9, is further divided by a longitudinal partition 11' having its forward vertical end connected to the partition 9, and its rear vertical end connected to the forward end 6' of the side walls 6. The space thus formed 100 provides an air-lock 12 (for the purpose hereinafter explained), and a working compartment 13, access to the latter being had through the journal 13' at the adjacent side of the tube, which is in open communication 105 110

therewith. The opening through the journal upon the opposite side of the tube is controlled by a door or hatch cover 14, so that when it is desired to use the compartment 12 as an air-lock, the door may be closed and the compartment thus sealed air- and water-tight. The space forward of the partition 9 constitutes a diving compartment 15, and the bottom of this compartment is formed with an opening 16 controlled by a door 17, (Figs. 4 and 5), so that exit may be made through the bottom of the vessel 4 from the diving compartment or chamber 15, and operations or observations carried out as will be well understood. The partition 9 is formed with a doorway 18 controlled by a door 19 as shown in Fig. 4. When it is desired to open the door 17, one first enters the diving compartment 15, then closes and seals the door 19 and admits sufficient quantity of compressed air to counterbalance the external pressure to thus prevent ingress of water to the compartment 15 when the door 17 is open.

Within the working compartment 13 is mounted a cylinder 20, open at its lower end and closed at its upper end by a stuffing box 21; and working within this cylinder 20 is a piston 22 having a hollow stem 23 extending upwardly therefrom, and with a depending cylindrical section 22', to the lower end of which is connected a casing 24 having journals in which is mounted a shaft 26 having traction wheels 27 mounted upon its outer ends. Keyed to the shaft 26 is a beveled gear wheel 28 with which meshes a pinion 29 carried at the lower end of a shaft 30 journaled at its lower end in the casing 24 and extending upwardly through the hollow stem 23 and through the stuffing box 21. To the upper end of the shaft 30 is swiveled a block 32 to which is connected a cable or chain 33 which passes over a sheave 34 journaled in a casting or casing 35 mounted upon the upper ends of tubes 36 and 37, extending from a casting 38 secured to the top of the vessel 4. The cable or chain 33 extends upwardly through the tube 36 around the sheave 34 and downwardly through the tube 37 and has its end connected to a rod 40 working through a stuffing box 41 connected to the top of the vessel 4. The lower end of the rod 40 is connected by a suitable coupling (not shown) from which extends a cable or chain 43 which passes over guide pulleys 44 and 45, (see Fig. 7) and has its opposite end connected to a coupling 46 carried at the upper end of a piston rod 47 extending from a piston (not shown), working in a cylinder 49 mounted within the vessel 4. Tapped into the upper end of the cylinder 49, above the piston, is a pipe 50 (Fig. 7), for admitting water or air under pressure for forcing the piston downwardly into the cylinder 49

to thus, through its connections with the shaft 30 and its co-acting parts, elevate the traction wheels 27 to thus adjust the bottom of the vessel 4 toward or away from the water-bed being operated upon. The pipe 50, it will be understood, will be extended from a suitable hydraulic or compressed air supply (not shown), located within the vessel 4. If desired, it may extend up through the tube 3 to suitable supply devices located upon the surface vessel 1.

The upper end of the shaft 30 is formed with a spline, and keyed upon the said shaft is a beveled pinion 51, (Fig. 8) which is mounted within the casting 38; and meshing the pinion 51 is a beveled pinion 52 carried at the upper end of a shaft 53 having at its lower end a worm wheel 54 meshed by a worm 55 carried at the outer end of a shaft 56 of a motor 57 mounted within the working compartment 13 of the vessel 4.

By the foregoing construction, it will be apparent that when the motor 57 is energized, the shaft 30 will be rotated and motion thus imparted to the traction wheels 27 to propel the vessel 4 over the surface of the water-bed, and to thus relieve the propellant force of the surface vessel. In order to rotate the traction wheels 27 on their vertical axis to steer the vessel over a given course, and to keep the same in longitudinal alinement with the surface vessel 1, I provide the hollow stem 23 with a hollow extension 23' upon which is keyed a worm wheel 58 (Figs. 7 and 8), which is meshed by a worm 59, shown in dotted lines in Fig. 4, carried at the inner end of a shaft 60, journaled at its inner end in a casing 61 surrounding the worm wheel 58, and in a stuffing box 62 fastened upon the transverse partition 9. The outer end of the shaft 60 extends into the diving compartment 15, and is provided with a hand wheel 63 by which the piston and its parts 23 23' and 22' may be rotated in order to steer the vessel 4 over any given course.

Mounted in the extreme forward end of the vessel 4 is a motor 65 having the lower end of its shaft 66 journaled in a suitable bearing 66' mounted upon the top of a plate 67 or casting 67 arranged within the lower forward end of the vessel 4. The plate 67 has a horizontal member and a vertical member, as shown in Fig. 5, and these members form the corresponding walls of a recess at the forward end of the vessel 4, and which is open to the surrounding body of water for the purpose hereinafter appearing. The shaft 66 of the motor 65 has a worm 69 keyed thereon, and meshing with a worm 70 carried by a shaft 71 journaled in a casing 72 which completely incloses the worm 69 and the worm wheel 70. The outer end of the shaft 71 is provided with disks 73 (Fig. 6), having wrist pins 74 upon which

are journaled the upper ends of connecting rods 75, the lower ends of which are pivotally connected to cross-heads 76 movable vertically in bearings 77 supported by suitable framework 78 mounted upon vertical stanchions 79 located in the extreme forward end of the vessel 4.

To the cross-heads 76 are connected vertically reciprocating shafts 80 having their lower ends operating in stuffing boxes 81 secured to the plate 67, the extreme lower ends of the said reciprocating shafts 80 being provided with disks 82, as shown in Fig. 5. The casing 72 is provided with an extension 83 to which is connected a cable 84 extending over a pulley 85 mounted in a bracket depending from the top of the vessel 4, the free end of the cable being wound upon a drum 86 mounted in suitable bearings 87 secured to one of the vertical walls of the vessel 4, and having a hand wheel 88 by which the cable 84 may be wound or unwound in order to raise or lower the disks 82 toward or away from the water-bed. By the arrangement just described, when the motor 65 is energized, the shaft 71 will be rotated so as to reciprocate the shafts 80 and thus cause the disks 82 to move toward and away from the water-bed, and thus, through suction, agitate and lift the material of the water-bed without injury to objects embedded therein. I have found from actual experience that by rapidly raising and lowering a disk in a body of water, and so arranging the disk that it will be immediately adjacent to the water-bed when in its lower-most position, the material of the water-bed will be sucked up, or "dug up," as it were, without injury to the embedded objects, and that this feature of my invention is particularly applicable in digging clams without injury to the same, since I avoid the necessity of forcing a prong, rake, or other excavating device into the water-bed in order to uncover them.

Extending through the diving compartment 15 and opening through the top and bottom of the vessel 4 is a well 90 through which is extended a suction pipe 91, shown in dotted lines in Figs. 1 and 2, extending from a suction pump (not shown), located upon the surface vessel 1, or upon a barge (not shown) operating in connection with my apparatus.

To the lower end of the suction pipe 91 is connected a scoop 92, shown in dotted lines in Fig. 2, similar to that shown in my aforesaid Patent No. 1,097,722. As the construction of the scoop and the connection of the suction pipe thereto forms no part of the present invention, I do not consider it necessary to describe this feature in detail. However, it might be stated that when the disks 82 are reciprocated, and the

soil of the water-bed thus agitated, or "dug up," the clams or other objects embedded in the water-bed will be drawn up to the surface and collected by the scoop as the vessel is moved over its course, and from the scoop will be drawn up by the suction 70 through the pipe 91 and delivered either to the surface vessel 1, or the barge, as the case may be.

95 and 95' designate guy lines connecting the surface vessel 1 with the submersible vessel 4 for holding said submersible vessel 4 in rigid relation to the surface vessel 1 during all degrees of submergence, and to thus relieve the strain upon the tube 3 due to the rolling motion of the surface vessel, especially when the apparatus is operating in a rough sea, the said lines 95 and 95' being also designed for holding the submersible vessel 4 on an even keel at all degrees of submergence.

96 designates a lifting cable extending from a suitable drum or winch (not shown), located upon the surface vessel, and having its lower end connected to the tube 3, whereby the depth of submergence of the said vessel 4 may be controlled when the vessel 4 has negative buoyancy, it being understood that when operating over a water-bed with the vessel 4 under negative buoyancy, the traction wheels 27 will be caused to rest upon the water-bed with sufficient weight to make them effective, and that by the employment of the lifting cable 96, the vessel 4 may be elevated without blowing the compartment or compartments 11, to avoid an obstruction such as a projecting rock, or a sunken vessel. As shown in dotted lines in Fig. 1 of the drawings, the guy lines 95 and 95' hold the vessel 4 on an even keel during all degrees of submergence. When the vessel 4 is elevated to the surface, it is slightly elevated at the bow, thus facilitating the transportation of the apparatus.

97 designates a drum mounted upon the deck of the submersible vessel 4, around which is wound a cable controlling an anchor weight 97' (Fig. 1), whereby the vessel 4 may be securely anchored in a given position, notwithstanding the rolling motion of the surface vessel 1. The drum 97 is mounted in a bracket 98, and the shaft of the drum carries a worm wheel 99, shown in dotted lines in Fig. 5. The worm wheel 99 is meshed by a worm 100 (also shown in dotted lines in Fig. 5), carried at the upper end of a vertically positioned shaft 101 extending downwardly into the diving compartment 15, and having its lower end provided with a handle shown as a crank 102, by which the shaft is operated. A stuffing box 103 surrounds the shaft and the opening in the deck of the vessel 4 through which the said shaft passes, to prevent ingress

of water to the working compartment around the bearing of the shaft as will be well understood.

105 and 106 designate sight openings arranged respectively in the sides of the vessel 4, and in the vertical wall of the plate 67. 107 designates a lamp arranged opposite an opening in the vertical member of the plate 67, Fig. 5 between the sight openings 106, 10 and said opening is protected by a plate glass window 108, whereby the water surrounding the disks 82 may be lighted up to thus enable the occupants of the diving compartment 15 to view the water-bed being operated upon.

Water is admitted to the ballast compartment or compartments of the submersible vessel 4, through suitable valves (not shown), and water is expelled from the said compartment or compartments either by a pump (not shown), or by air pressure supplied from a tank 110 mounted in the diving compartment 15, and from which tank is extended an air-pipe 111, having the controlling valve 112 and also having branches 111' leading into the said ballast compartment or compartments. One of the branches 111 is provided with a valve 112' for admitting air to the air-lock 12 as may be desired. Air is supplied to the tank 110 through a tank 113 mounted in the working compartment 13, and connected to the said tank 110 through a pipe 114, as shown in Fig. 4. The tank 113 is supplied with compressed air through a pipe 115 extending from a suitable air compressor (not shown), carried by the surface vessel, said pipe 115 being extended down through the tube 3, and through the journals 13', as shown in Fig. 4.

40 In operation the submersible vessel 4 is propelled by the surface vessel 1, to the locality over which the water-bed is to be operated upon. Water-ballast is then let into the compartment or compartments 11 to overcome the buoyancy of the vessel 4 and cause it to sink to the bottom, and the traction wheels 27 are then adjusted into proper relation with the water-bed. The said traction wheels are then set in motion, as is also, 45 the motor 65 for operating the churning disks 82, and as the vessels are propelled, the excavated material will be taken up through the pipe 91 and delivered either to the surface vessel 1, or to the barges working in connection therewith.

50 In practice, I purpose providing the surface vessel 1 with a propeller 116 located in an opening formed in the keel of said vessel for facilitating the steering of said vessel in lateral directions, whereby it may be more readily maintained in a parallel course with respect to the vessel 4.

Also, in practice, I purpose providing the submersible vessel 4 with a cleat 117, so that 55 the tube may be firmly locked to the said

vessel when the latter is floating on the surface, as during transportation.

While I have shown various arrangements in my aforesaid patents for holding the upper end of a submersible tube in the well of a surface vessel, in the present construction I purpose mounting the said tube 3 in the well in a manner I will now describe. As shown, the upper end of the tube is provided with an elbow 3' to which is rigidly connected a bracket 300 having a journal 301 upon which is securely bolted a yoke 302 having pintles 304, which rest in bearings 305 fastened to the walls 2' of the well 2 of the surface vessel 1, whereby movement of the tube to conform to the movement of the vessel is permitted. The arrangement shown, it will, of course, be understood, also permits vertical movement of the tube 3.

It will be understood, that, in practice, suitable yielding connections will be arranged in the guy lines to permit a certain amount of yielding movement in the lines to thus relieve the strain thereon during excessive movement of the surface vessel. However, as this feature of my invention will be readily appreciated by engineers skilled in the art to which the invention relates, it is not thought necessary to illustrate, or to describe the same herein.

From the foregoing, it will be seen that I provide an apparatus that is particularly designed for submarine operations, whereby the depth of submergence of the submarine vessel may not only be controlled, but, also, one in which communication between the surface vessel and the submersible vessel may be had at all times irrespective of the depth of submergence of the submarine vessel 4, and furthermore, that by the lifting cable 96, the submarine vessel may be held above the water-bed when the said vessel 4 is under positive buoyancy, thereby avoiding the necessity of blowing the compartment or compartments of the submersible vessel 4 to give it requisite buoyancy to avoid an obstruction, and whereby the said vessel 4 may be held free of the water-bed, or an encountered obstruction. When transporting the apparatus, it will be understood the submarine vessel 4 travels upon the surface of the water under its own buoyancy, and is held rigidly to the surface vessel 1 by means of the lines 95 and 95', which, in combination with the tube 3, securely hold the vessel 4 in longitudinal alinement with the surface vessel 1, and thus cause the said vessel to easily ride the seas.

What I claim is:

1. Apparatus of the kind described, comprising a surface vessel and a submersible vessel, and means connecting the same and adapted to project and locate the submersible vessel in advance of the surface vessel.

2. Apparatus of the kind described, com-

prising a surface vessel and a submersible vessel, and means connecting the same and pivotally attached thereto and adapted to project and locate the submersible vessel in 5 advance of the surface vessel.

3. Apparatus of the kind described, comprising a surface vessel and a submersible vessel, and means pivotally connecting the 10 vessels and affording communication between them and projected forwardly from the surface vessel and adapted to propel the submersible vessel in advance of the surface vessel.

4. Apparatus of the kind described, comprising a surface vessel provided with a 15 forward well opening at the bow, a tube pivotally mounted at one end in said well, and a submersible vessel pivotally connected aft with the other end of the tube and 20 leading the surface vessel and equipped with exploration and other working apparatus.

5. Apparatus of the kind described in 25 claim 4 in which the well is provided with a horizontally arranged pivoting member to which the tube is yoked.

6. Apparatus of the kind described in 30 claim 4, in which the tube has a pivot member and the well has a rocking yoke in which said pivot member is fitted.

7. Apparatus of the kind described in 35 claim 4 in which means are provided for accommodating relative movement of said surface vessel and tube, same comprising a connection between the two provided with pivotal joints arranged on axes normal to each other.

8. Apparatus of the kind described in 40 claim 4, in which the submersible vessel has an amidship section in which the tube is journaled, said section being divided into a working compartment in open communica-

tion with said tube and an air-lock in closable communication with said tube.

9. Apparatus of the kind described in 45 claim 4 in which the submersible vessel has an air-lock arranged amidship therein, a diving compartment arranged forward, and a door interposed between the air-lock and the diving compartment.

10. The combination with a surface vessel, of a submersible vessel having ballast 50 compartments of sufficient capacity to destroy the buoyancy of the same, and a tubular structure journaled to said surface vessel and projecting forwardly therefrom and 55 also journaled to said submersible vessel and affording means of communication between the two vessels.

11. The combination with a surface vessel having a forward longitudinal well, of 60 a submersible vessel having ballast compartments of sufficient capacity to destroy the buoyancy of the same and also having an aft longitudinal well and an amidship section, and a tubular structure journaled to 65 said vessels substantially amidship and affording dry communication between said vessels.

12. The combination with a surface vessel, of a communicating submersible vessel 70 having independent propelling mechanism, means to raise and lower said propelling mechanism, and means to turn and thereby utilize the propelling mechanism for steering purposes.

In testimony whereof I have hereunto set 75 my hand this 14th day of December, A. D. 1916.

SIMON LAKE.
